DESIGN FOR A BOX OR SIMILAR ARTICLE

Lucien Lelong, Paris, France, assignor to Lucien LeLong, Inc., Chicago, Ill., a corporation of Illinois

Application September 1, 1939, Serial No. 86,994

Term of patent 14 years

To all whom it may concern:

Be it known that I, Lucien Lelong, a citizen of the Republic of France, and a resident of the city of Paris, France, have invented a new, original, and ornamental Design for a Box or Similar Article, of which the following is a specification, reference being had to the accompanying drawing, forming a part thereof.

On the drawing:

I claim:

The ornamental design for a box or similar article, as shown.

LUCIEN LELONG.
